**STORAGE DRUM FOR MAGNETIC RECORDING
AND REPRODUCTION OF DATA IN IMPULSE
FORM**

Armin Krause and Helmut Keitel, Wilhelmshaven, Germany, assignors to Olympia Werke A.G., Wilhelmshaven, Germany

Filed Oct. 19, 1960, Ser. No. 63,072

Term of patent 14 years

(Cl. D26—5)

Fig. 1.

Fig. 2.

FIG. 1 is a perspective view from one side of the storage drum for magnetic recording and reproduction of data in impulse form, showing our new design; and

FIG. 2 is a perspective view from another side.

The essential features of the design reside in the portions shown in full lines on the drawing.

We claim:

The ornamental design for a storage drum for magnetic

recording and reproduction of data in impulse form, as shown and described.
